UNITED STATES PATENT OFFICE.

PERCY ROBERTS, OF SURBITON, ENGLAND, ASSIGNOR OF ONE-HALF TO G. D. PETERS & COMPANY, LIMITED, OF SLOUGH, BUCKINGHAM, ENGLAND.

SHIP'S HULL AND OTHER IRON OR STEEL VESSEL OR CONTAINER.

Application filed July 12, 1921. Serial No. 484,131.

To all whom it may concern:

Be it known that I, Percy Roberts, a subject of the King of Great Britain and Ireland, residing at Surbiton, in the county 5 of Surrey, England (whose post-office address is 28 Adelaide Road, Surbiton, in the county of Surrey, England), have invented certain new and useful Improvements in or Relating to Ships' Hulls and Other Iron 10 or Steel Vessels or Containers; and I do hereby declare the following to be a full, clear and exact description of the invention, such as will enable others skilled in the art to which it appertains to make and use the 15 same.

This invention has for its object improvements in or relating to ships' hulls and other iron or steel vessels or containers, for instance boilers, tanks and the like, whereby 20 increased strength and rigidity are obtained due to the plates of which the hull, or the like, is built up being practically formed as one piece due to the improved method of locking and welding the plates 25 together according to this invention. By means of the invention fewer inside frames or stiffening members will be required in a ship's hull with a resulting increase in cargo space and reduction in weight of the 30 vessel whereby more cargo can be carried on a given draught. Reduction in weight of the vessel also obtains by reason of the fact that there is no overlap of the plates. Further the outside of the hull constructed 35 according to this invention presents a smooth surface, being free from overlapping joints, with the result that skin friction is reduced and economy in power and fuel consumption obtained; also corrosion 40 cannot set up between plates as may happen with overlapping plates.

According to this invention the plates of which a ship's hull, or other vessel or container, is formed are, in addition to being 45 secured together by being welded to each other along their edges, locked together by suitably shaped members or plates inserted in correspondingly shaped apertures or

holes in the plates, the edges of these apertures or holes and of the locking members 50 being suitably shaped or bevelled to provide a bed, channel or recess for the metal added or run in by the welding operation by which the plates are welded together, and the locking members being of such configuration 55 that the apertures are free from any sharp angles that might tend to produce weakening cracks in the metal plates. The welding may be done by the oxy-acetylene, electric or other suitable method of welding. The aforesaid apertures in the plates 60 for receiving the locking members may have approximately the shape of the figure 8, or may be of other suitable shape. The plates are placed edge to edge and butt welded 65 along their edges, these edges are suitably shaped or bevelled to provide a bed for the welding metal.

In one embodiment of the invention a suitable number of locking apertures of such 70 formation as not to possess sharp angles and each forming one half of a complete locking aperture, is formed in each plate these apertures being so situated that they break or open through the adjacent edges 75 of the plates so that when the plates are placed edge to edge the openings register and the complete locking aperture is thus formed.

The hereinbefore mentioned locking pieces 80 or members may be stamped out of plate of the same thickness as that of the plates forming the hull, or these locking pieces may be drop forgings and, further may be formed as projections from a base portion, 85 plate or flange which may be of a size suitably larger than the locking pieces and the holes in which they fit so that the said base portion will overlap to a desired extent and lie on the inside of the hull plate or plates 90 thus giving increased stiffness or strength to the hull plates.

In constructing a ship's hull the plates may be spot welded or they may be riveted to the frames, and the hereinbefore mentioned locking apertures or holes may then 95

be formed in the plates by means of the oxy-acetylene blow pipe, or by a suitable cutting appliance. Or these locking holes might be made in the plates, for instance by 5 punching, before they are attached to the frames.

In an alternative construction, where the plates are placed edge to edge and butt welded together instead of providing locking holes or apertures in the plates and welding locking pieces therein as above mentioned, the plates may be formed with 10 curved angular dovetail or other suitably shaped recesses in one edge and correspondingly shaped projections on the opposite edge so that when the plates are assembled the projections on one plate will enter the recesses in the next plate, these projections and recesses having their edges bevelled 15 so as to form a recess or bed for the welding metal by which the projections on one plate are welded to the next plate.

The invention is illustrated by the accompanying drawings, and will now be described with reference thereto.

Fig. 1 shows two portions of plate joined together according to the invention.

Fig. 2 is a section corresponding to the line A, A of Fig. 1.

Fig. 3 shows in side elevation one of the locking pieces.

Fig. 4 shows an edge portion of one of the plates.

Fig. 5 is a section corresponding to the line B B of Fig. 4.

Figs. 6, 7 and 8 are sections corresponding to the line C C, D D, and E E respectively of Fig. 1.

Fig. 9 illustrates a section on the line 40 F F of Fig. 1 assuming that the plates to be joined were curved instead of straight.

Fig. 10 is a similar view to Fig. 1 illustrating modifications in the shape of the locking pieces.

Fig. 11 is also a similar view to Fig. 1 illustrating a further modification.

Fig. 12 is a section corresponding to the line G G of Fig. 11.

Fig. 13 is another view similar to Fig. 1, 50 illustrating a further modification, and,

Fig. 14 is a section corresponding to the line H H of Fig. 13.

Fig. 1 shows two portions of plate 1 and 2 to be joined by being welded at 3 along 55 their abutting edges and by locking pieces 4, taking into apertures 5, punched or otherwise formed in the plates 1 and 2, and welded at 6 to said plates. The locking piece 4 shewn at J in Fig. 1 has rounded ends 60 connected by curved side portions so that as will be seen there is not any sharp angle from which a crack along the plate might spring. Fig. 2 shows a section taken on the line A—A, Fig. 1, of the plates 1 and 2 and locking piece 4, after being welded. A por-

tion of the plate 1 with aperture 5 provided in one edge is shewn in Figs. 4 and 5. The edges of each plate and of the apertures are bevelled as shewn at 1^a, 5^a, respectively, and the edges of the locking pieces 4 are 70 also bevelled as shewn at 4^a, Fig. 3, so that when the plates and locking pieces are assembled a bed or channel is formed to receive the metal added by the welding operation. It will be seen that plates joined 75 as described present a smooth surface on each side, being free from overlapping joints or protuberances.

In an alternative embodiment of the invention shewn at K in Fig. 1, the locking 80 piece or member 4 may be a forging of a greater thickness than the plates 1 and 2 to be joined and be so formed that at one side (which will be at the inner side of the structure in the case of a ship's hull) said 85 locking member has a portion or flange 7 which overlaps and lies against the plates 1 and 2 around the apertures cut therein, and said flange 7 is welded around its edges to said plates 1 and 2 as indicated at 8 in 90 Fig. 6, which figure is a section on the line C—C, Fig. 1, after the welding operation has been performed.

Instead of the plates 1 and 2 having apertures formed in their abutting edges holes 95 may be punched or drilled adjacent said edges each hole to receive a projection 9 on a base plate 10, as shown at L in Fig. 1. The edges of the holes and the projections 9 are bevelled so that a channel or bed is 100 formed in each case to receive the metal added in the welding operation. In addition to the projections 9 being welded to the plates (as indicated at 11, Fig. 7) the base plate is welded around its edges to the 105 plates 1 and 2 as indicated at 12 in Fig. 7, which latter figure is a section on the line D—D, Fig. 1 after the welding has taken place.

In some cases the base plate 10 of each locking member has formed on it six projections 9, as shewn at M, Fig. 1, three of which take into holes in plate 1 and three into holes in plate 2, this construction giving even greater strength and rigidity at 115 the joints of plates.

In Fig. 1, the plates 1 and 2 are shewn as flat plates, but the invention is equally applicable to joining curved plates as used in boiler and tank construction, and in the 120 joining of such plates any of the locking pieces previously described may be employed, or a combination of such locking pieces may be employed as illustrated at N in Fig. 1. Fig. 9 is a section on the line 125 F—F, of Fig. 1 except that curved plates 1 and 2 are shewn and the base plate 10 is curved to correspond to the curved plates to be joined. Four bevelled projections 9 are shewn on the plate 10, two adapted to 130

take into holes in one plate and two into holes in the other, and said plates, base plate and projections, as well as the abutting edges of the plates 1 and 2, are welded 5 as already described. In addition apertures are formed in the edges of the plates 1 and 2 to receive a bevelled locking piece 4 of similar form to that shewn in Figs. 1 and 3 but curved as required to suit the curvature of the plates and being also welded to the plates as before described.

The locking pieces 4 may be of any suitable shape such as will hold the plates against strains tending to move them apart 15 in the planes in which they lie, and such as not to present any sharp angles liable to lead to fractures in the plates. A number of shapes they might take is illustrated, more or less diagrammatically, in Fig. 10,— 20 whether or not the locking pieces have flanges adapted to overlap the plates around the recesses in their edges. It may in some cases be considered preferable to form the locking pieces of substantially the shape 25 shown at the extreme left of Fig. 10, as owing to the formation of the central portion of the locking piece (i. e., the provisions of the outwardly projecting portions 4^b) the angles or corners formed by cutting 30 out the apertures 5, and marked 5^b in Fig. 4, will be rendered much less sharp.

Another embodiment of the invention is illustrated by Figs. 11 to 14, inclusive, in which instead of employing locking members 35 formed separately from the plates to be joined the locking members are integral therewith, said plates having their edges so formed that interlocking projections 13 and recesses 14 are provided. Where the 40 plates to be joined are relatively long and narrow and are to be joined end to end they may be formed at their ends as shewn in Fig. 11, the abutting end edges being bevelled so that a bed or channel is provided 45 to receive the metal employed in the welding process. Fig. 12 is a section on line G—G, Fig. 11, but showing the plates after being welded. If it should be desired to join relatively long edges of the plates together 50 this may be done, according to this embodiment of the invention, by forming the plates at their edge regions as shewn in Fig. 13 so that projections 13 and recesses 14 alternate along the edge of each plate 55 the parts interlocking when placed together. Fig. 14 is a section on the line H—H, Fig. 13, taken after the plates have been welded together.

Although in the embodiments of the invention illustrated in the drawings the abutting edges of the plates to be joined, and also the edges of the plates at the apertures and the edges of the locking pieces, are in every case shown bevelled, it will be 60 understood that, if desired, the edge of one

plate only, and the edge of the recess only or of the locking piece only, might be so bevelled or chamfered provided that by so doing a channel or bed of sufficient cross sectional area be left for the metal added in 70 the welding operation.

What I claim as my invention and desire to secure by Letters Patent is:—

1. For use in the construction of ships' hulls and other iron or steel vessels or containers and in combination with plates arranged edge to edge and adapted to be welded together at adjacent edges, locking members each comprising a base portion adapted to lie across the joint between and to be welded to such plates and having means projecting from the base portion adapted to enter apertures in, and to be welded to, said plates.

2. For use in the construction of ships' hulls and other iron or steel vessels or containers and in combination with plates arranged edge to edge and adapted to be welded together at adjacent edges, locking members each comprising a base portion 80 adapted to lie across the joint between and to be welded to such plates and having a plurality of projections on the base portion adapted to enter apertures in the plates adjacent the edges thereof and to be welded to 95 said plates.

3. In the construction of ships' hulls and other iron or steel vessels or containers, the combination of plates adapted to be arranged edge to edge and to be welded together at 100 their edges and having apertures in them, and locking members each comprising a base portion adapted to lie across the joint between and to be welded to the said plates and means projecting from the base portion 105 adapted to enter the apertures in, and to be welded to, said plates, for the purposes set forth.

4. In the construction of ships' hulls and other iron or steel vessels or containers, the combination of plates adapted to be arranged edge to edge and to be welded together at 110 their edges and having apertures in them adjacent their edges, and locking members each comprising a base portion 115 adapted to lie across the joint between and to be welded to the said plates and a plurality of projections on the base portion adapted to enter the apertures in, and to be welded to, said plates, for the purposes set 120 forth.

5. In the construction of ships' hulls and other iron or steel vessels or containers, the combination of plates adapted to be arranged edge to edge and to be welded together at 125 their edges and having registering apertures in their adjacent edges and a plurality of holes in each plate adjacent each said aperture, a locking member at each group of holes and apertures and comprising 130

ing a base portion adapted to lie across the joint between and be welded to the said plates and having a plurality of projections on the base portion adapted to enter the appropriate holes in and to be welded to the said plates, and a locking member of the same thickness as the plates to be joined adapted to enter the registering apertures in and be welded to the said plates, for the purposes set forth. 10

In testimony whereof I affix my signature, in presence of two witnesses.

PERCY ROBERTS.
